(57) **CLAIM**

The ornamental design for a telescopic tool, as shown.

DESCRIPTION

FIG. 1 is a side perspective view of the telescopic tool in an extended condition with a first form of the interchangeable end.

FIG. 2 is a partial side elevation view of the telescopic tool of FIG. 1 in an extended condition.

FIG. 3 is another partial side elevation view of the telescopic tool of FIG. 1 in an extended condition.

FIG. 4 is a top plain view of the telescopic tool of FIG. 1.

FIG. 5 is an underneath plain view of the telescopic tool of FIG. 1.

FIG. 6 is a transverse cross-section view of the line 6 to 6 of FIG. 3.

FIG. 7 is a top perspective view of the telescopic tool of FIG. 1 in a retracted condition with the first form of the interchangeable end.

FIG. 8 is a top perspective view of the telescopic tool of FIG. 1 in a fully extended condition; and,

FIG. 9 is a partial exploded view of the telescopic tool of FIG. 1.
